UNITED STATES PATENT OFFICE.

FRANCIS G. DAVIS, OF WATERTOWN, NEW YORK, ASSIGNOR TO H. H. BABCOCK COMPANY, OF WATERTOWN, NEW YORK, A CORPORATION OF NEW YORK.

WHIFFLETREE-COUPING.

No. 820,918.

Specification of Letters Patent.

Patented May 15, 1906.

Application filed May 11, 1905. Serial No. 259,895.

To all whom it may concern:

Be it known that I, FRANCIS G. DAVIS, of Watertown, in the county of Jefferson, in the State of New York, have invented new and 5 useful Improvements in Whiffletree - Couplings, of which the following, taken in connection with the accompanying drawings, is a full, clear, and exact description.

This invention relates to certain improvements in whiffletree-couplings, in which the primary object is to interfit two wearing-plates one upon and within the other, so as to produce a comparatively broad dust-proof bearing upon which the whiffletree may freely 10 swing or turn without unduly straining the parts and at the same time to clamp these plates together by a suitable bolt without passing said bolt through the whiffletree or allowing it to turn therewith, thereby obviating in a measure the strain upon the clamping-bolt and assuring a more permanent bearing.

Other objects and uses relating to the specific construction of the coupling will be 15 brought out in the following description.

In the drawings, Figure 1 is a top plan of a portion of a cross-bar and whiffletree coupled together by my improved coupling. Fig. 2 is a front elevation, partly in section, of the 20 parts seen in Fig. 1. Fig. 3 is a transverse sectional view taken on line 3 3, Fig. 1. Figs. 4, 5, and 6 are perspective views, respectively, of the upper and lower coupling-plates and the bolt for clamping them in operative 25 position.

A and B represent, respectively, portions of a cross-bar and whiffletree of a pole or thills which are pivotally coupled together by two circular metal plates 1 and 2 and a clamping-bolt 3. These plates 1 and 2 are of substantially the same diameter, which is about equal to the transverse width of the cross-bar A and B and are each provided with a central aperture for receiving the bolt 3, which is passed through a vertical aperture 4 in the bar A and has its upper end provided with a head 5, which enters the recess 6 in the lower face of the whiffletree B.

The coupling-plate 1 is preferably, cup-shaped and formed with a substantially flat bottom resting upon the upper face of the bar A and secured thereto by suitable fastening means, as screws 7, which are passed through

apertures 8 in the bottom of the plate 1 at opposite sides of its center and serve to firmly 55 secure said plate to the bar A. This plate 1 is also formed with an annular marginal flange 9 and a central hollow boss 10, which projects some distance above the upper edges of the flange 9 and closely fits within an aperture 11 centrally within the upper plate 2, with its end disposed in a plane substantially coincident with the upper end of a similar boss 12, which is formed centrally upon the plate 2. This latter plate 2 is seated upon 60 the upper horizontal edge of the marginal flange 9 of the plate 1 and has a reduced portion depending from its lower side, forming an annular shoulder 13, which projects into and has an easy-turning fit within the upper 65 part of said flange 9, said plate 2 being rigidly secured to the lower face of the whiffletree B by bolts 14, which are passed through apertures in the whiffletree B and plate 2 and have their lower ends threaded and project- 70 ing into the space within the flange 9 and between the plates 1 and 2, these threaded ends being engaged by suitable nuts 15, which are therefore concealed between the plates 1 and 2 and within the annular flange 9 at opposite 75 sides of the central boss of the plate 1.

The head 5 of the bolt 3 rests upon the top face of the hollow boss 12 of the coupling-plate 2 and has its threaded shank extending downwardly through the hollow boss 10 and aperture 4 in the bar A, which threaded end is engaged by a suitable nut 16, bearing against the lower side of said bar A, thereby clamping the coupling-plates 1 and head 2 in operative relation one upon the other, and 80 thereby retaining the whiffletree in operative position upon the cross-bar.

It will be observed that the upper face of the boss 11 terminates in a plane slightly below the upper face of the boss 12 and the 85 plate 2, the object of which is to allow for a slight take-up to compensate for the wear of the contiguous faces of the plates 1 and 2 and at the same time to afford additional bearing for the swinging whiffletree B.

It will also be observed that the boss 10 of the lower plate 1 is provided with a keyway 17, which receives a key 18 on the upper end of the bolt 3 directly under the head 5, by which the bolt is locked to the lower plate 1 105 and is thereby prevented from turning with

the whiffletree B, so that as the whiffletree turns or swings upon its axis the upper face of the boss 12 of the plate 2 rides around against the lower face of the head 5.

5 In assembling the parts of my invention the lower coupling-plate 1 is first secured to the cross-bar A by the screws 7, and the bolt 3 is inserted through the central aperture in the plate 2, with its head resting against the end 10 face of the boss 12, in which position the plate 2 is clamped to the lower face of the whiffletree B by means of the bolts 14, so that the boss 12 and head 5 enter the recess 6.

The whiffletree, with the plate 2 and bolt 3 thereon, are then brought into operative position upon the lower plate 1, with the shank of the bolt 3 extending through the boss 10 and aperture 4, after which the nut 16 is engaged with the lower threaded end of the bolt and 20 lower face of the cross-bar A, the whiffletree being thus held in place by a single non-rotatable bolt, which simply serves to retain the whiffletree in operative position against upward displacement, but is relieved entirely from lateral strain or wear by reason of the 25 fact that the whiffletree-coupling plate 2 turns solely upon the lower plate 1 and its central boss 10 and together with the lower plate forms an intervening pocket or receptacle for a suitable lubricant, as grease or oil, 30 for lubricating the substantially dust-proof joint or bearings between said plates.

Having thus described my invention, what I claim, and desire to secure by Letters Patent, is—

35 1. In a whiffletree-coupling, the combination with a cross-bar and whiffletree, of a cup-shape plate secured to the cross-bar and provided with a central aperture, a plate secured 40 to the lower face of the whiffletree and rotatably fitted upon and within the open upper end of the cup-shape plate forming therewith an intervening space for the reception of a lubricant, said second plate being provided 45 with a central aperture and a surrounding boss and a clamping-bolt passed through the apertures in said plates and having its upper end provided with a head engaging the upper face of the boss on the rotatable plate and 50 its lower end secured to the cross-bar.

55 2. In combination with a cross-bar and whiffletree, a wearing-plate secured to the top face of the cross-bar and provided with a marginal annular flange and a central tubular boss extending above the annular flange, a second wearing-plate secured to the lower

face of the whiffletree and having a central aperture receiving and fitting upon the upper end of said boss, said second plate bearing upon the marginal flange of the first-named 60 plate bolts passing through the whiffletree and carrying nuts located in the space between said plates and a clamping-bolt secured to the cross-bar and engaged with the second wearing-plate for holding the latter in operative position upon the first-named plate.

3. In combination with a cross-bar and whiffletree, the cross-bar being provided with a central aperture, a wearing-plate secured to the top face of the cross-bar and provided 70 with an annular flange and a central aperture aligned with the aperture in the cross-bar, a second wearing-plate secured to the under side of the whiffletree and bearing upon the top face of said flange and provided with a central aperture, a bolt having a bearing-face resting upon the top face of the second wearing-plate and provided with a threaded shank extending through the apertures in the 75 first-named wearing-plate and cross-bar, and a key carried by the bolt and engaging a keyway in said wearing-plate for locking the bolt 80 against rotation.

4. In combination with a cross-bar and whiffletree, the cross-bar being provided with 85 a central aperture therethrough, a wearing-plate secured to the top face of the cross-bar and provided with a marginal upwardly-projecting annular flange and a central projecting boss projecting upwardly above the upper edge of the flange and provided with an aperture therethrough, a second wearing-plate secured to the under face of the whiffletree and having a portion thereof bearing upon the top face of the flange and, another portion 90 fitting within the flange, said second plate being provided with a central aperture receiving and fitting upon the boss of the first-named plate and a bolt engaging the top face of the second plate and passing through the 95 apertures in the first-named plate and cross-bar and clamped to said cross-arm, and a key carried by the bolt and engaging a keyway in 100 said wearing-plate for preventing the rotation of the first-named bolt in the first-named 105 plate.

In witness whereof I have hereunto set my hand this 8th day of May, 1905.

FRANCIS G. DAVIS.
